DESIGN FOR A COMBINED TOAST TRIMMING KNIFE AND BOARD

Everett Worthington and Findley Williams, Chicago, Ill., assignors to McGraw Electric Company, Chicago, Ill., a corporation of Delaware

Application July 27, 1935, Serial No. 57,829

Term of patent 3½ years

To all whom it may concern:

Be it known that we, Everett Worthington and Findley Williams, citizens of the United States, both residing at Chicago, in the county of Cook and State of Illinois, have invented a new, original, and ornamental Design for a Combined Toast Trimming Knife and Board, of which the following is a specification, reference being had to the accompanying drawing, forming part thereof, in which

Fig. 1 is a top plan view of the combined toast trimming knife and board, showing our design, Fig. 2 is a view in side elevation thereof, and Fig. 3 is an end view thereof.

We claim:

The ornamental design for a combined toast trimming knife and board as shown.

EVERETT WORTHINGTON.
FINDLEY WILLIAMS.
